UNITED STATES PATENT OFFICE.

WILLIAM B. GREGORY, OF LA FAYETTE, INDIANA.

DESIGN FOR A CAMPAIGN-MEDAL.

Specification forming part of Design No. 5,994, dated July 16, 1872.

Specification describing a Design for a Campaign-Medal, invented by W. B. GREGORY, of La Fayette, in the county of Tippecanoe and State of Indiana.

The nature of my design is fully represented in the accompanying drawing, to which reference is made.

The medals are stamped from thin sheet-brass or other suitable material, and are to contain photographs of the presidential candidates.

a represents an oval frame, the main part of which is an imitation of rope; *b*, two American flags, joining *a* and *c*; *c*, an oval frame, the

pattern of *a*, a line connecting the focuses of *c* being at right angles to *a*; *d*, fastenings to hold the pictures in their places.

What I claim as my invention, and for which I desire to secure Letters Patent, is—

A design for a campaign-medal, substantially as described, consisting of the oval frames *a* and *c*, and flags *b* *b*, arranged substantially as described.

W. B. GREGORY.
